UNITED STATES PATENT OFFICE

2,677,847

SUCTION CLEANER WITH CONVERTER CONNECTION

Donald G. Smellie, Canton, Ohio, assignor to The Hoover Company, North Canton, Ohio, a corporation of Ohio

Application November 10, 1949, Serial No. 126,539

5 Claims. (Cl. 15—333)

1

This invention relates to suction cleaners and more particularly to a new and improved mechanism for converting a cleaner from on-the-floor operation to dusting tool cleaning.

An object of the invention is to provide a suction cleaner having an improved mechanism for converting to off-the-floor or dusting tool cleaning. A further object is to provide a mechanism for sealing the converter tool to the source of suction. Another object is to provide a converter tool sealing mechanism which does not obstruct the suction air passageway during on-the-floor cleaning. Another object is to provide a converter tool closing mechanism which is effective in one position of the cleaner propelling handle. A further object is to provide an arrangement of parts whereby the converter tool, when connected, prevents movement of the cleaner propelling handle. Other objects and advantages of the invention will become apparent from the following description and drawings wherein:

Figure 1 is a side elevation with parts broken away showing the cleaner arranged for on-the-floor cleaning;

Figure 2 is a side elevation showing the converter attached to the cleaner for dusting tool cleaning; and

Figure 3 is a bottom view partly broken away of Figure 1.

The embodiment of the invention herein disclosed comprises a suction cleaner provided with a nozzle 10 from one end of which extends a bracket 11, and from the opposite end extends a conduit 12 providing an air passageway 13, the bracket 11 and conduit 12 each terminating in a trunnion 14 on which is rotatably mounted a motor-fan housing 15 having a fan chamber 16 and an unshown motor. The shaft 17 of the unshown motor supports a suction creating fan 18 and extends through the fan chamber eye 19 into the passageway 13 where it is provided with a pulley 20. A belt 21 extends from the pulley 20 through the passageway 13 to a surface agitating member 22 rotatably mounted in the nozzle 10. An opening 25 in the conduit 12 is normally closed by a removable cover 26 to provide access to the pulley 20. Extending from the fan chamber 16 is a discharge outlet 27 to which the lower end of a bag 28, only partly shown, is attached and the latter is supported at its upper end by a handle 29 rigidly mounted in the motor-fan housing 15 for movement therewith. The nozzle 10 has a mouth 30 defined by a perimeter lip 31, and the agitator projects below the lip 31 for engagement with the surface being cleaned

2

when the cleaner is employed for on-the-floor operation.

The cleaner is supported on front wheels 35—35 and rear wheels 36—36, the latter being mounted on brackets 37—37 extending from the cleaner body. The front wheels 35 are rotatably mounted on offset ends 38—38 of a shaft 39 having intermediate offset portions 40—40 rotatably attached to the cleaner body by brackets 41—41, and the mid-portion 42 of the shaft 39 is offset towards the motor-fan housing 15. A pair of torsion springs 43 are arranged about the shaft offsets 40 to rotate the shaft 39 clockwise, as viewed in Figure 1, against a nozzle adjusting sector 45 mounted on the housing 15.

The sector 45 is provided with a stop 46 at one end, a uniform arcuate portion 47 and a recess 48. When the shaft portion 42 engages the stop 46 the handle 29 is supported in its lowest operating position shown in Figure 1, and when the recess 48 receives the shaft portion 42 the handle is supported in storage or dusting tool cleaning position shown in Figure 2. The nozzle lip 31 is maintained in proper adjustment with respect to the surface 49 when the shaft portion 42 engages the uniform arcuate section 47, and is raised to off-the-floor cleaning position when the shaft portion 42 is disposed in the recess 48 as shown in Figure 2.

The rear end of the conduit 12 is provided with an opening 50 which is closed by a barrier 51 rotatably supported on a pin 52 mounted in the upper and lower walls 53 and 54 respectively of the conduit 12, and a torsion spring 55 urges the barrier 51 to its closed position. The barrier 51 has an arcuate portion 57 conforming to the rear periphery of the fan eye 19, and when in closed position forms a continuation of the fan eye 19 into the air passageway 13 rearwardly of the motor shaft 17. The arrangement of the arcuate barrier 57 as a continuation of the fan eye 19 prevents accumulation of dirt in the passageway 13 rearwardly of the motor shaft 17 when the cleaner is employed for on-the-floor operation. A portion 59 of the lower wall 54 of the passageway 13 is bowed downwardly from the fan eye 19 to direct the dirt-laden air from the nozzle mouth 30 to enter the fan eye 19 from the bowed portion 59. The upper wall 53 of the passageway 13 is provided with an arcuate wall 60 projecting into the air passageway 13 adjacent the front and upper periphery of the fan eye 19.

A converter 62 is insertable through the opening 50 into the air passageway 13 and comprises a cylindrical outer end 63 and a rectangular

3

shaped portion provided with side walls 64 and 65 and end walls 66—66, the latter terminating in an arcuate end wall 67. The inner side wall 64 is formed with an opening 68 which conforms to the fan eye 19, and the outer side wall 65 and the arcuate end wall 67 are provided with a slot 69 to arrange the inner end of the converter about the motor shaft 17 between the fan eye 19 and the belt 21. The top and bottom walls 53 and 54 of the conduit 12 extend rearwardly of the barrier 51 as indicated at 70—70 and function to guide the converter 62 into the air passageway 13 as shown in Figure 2.

Cooperating with the converter 62 is a converter closing member 75 formed on the housing 15 and has a portion 76 extending through the fan eye 19 into the air passageway 13 and is provided with an angular portion 77 having an arcuate end 78 to partially receive the motor shaft 17. The converter closing member 75 rotates with the handle 29 and the housing 15 and is movable beneath the arcuate wall 69 when the handle 29 is oscillated through its normal operating range, whereby the arcuate wall 69 prevents the converter closing member 75 from obstructing the flow of the dirt-laden air passing from the nozzle mouth 30 to the fan eye 19 during on-the-floor cleaning. When the handle 29 is in its storage or dusting tool cleaning position the converter closing member 75 is arranged forwardly of the motor shaft 17, as shown in Figure 2, and upon inserting the converter 62 the member 75 enters the converter slot 69 to seal the nozzle mouth 30 from the fan chamber and confine the flow of air through the converter to the fan eye 19.

When the cleaner is employed for on-the-floor operation, the converter 62 is disconnected, and the agitator 22 is rotated to dislodge dirt from the floor covering 49. The resulting dirt-laden air passes through the nozzle mouth 30, air passageway 13 and fan eye 19 into the fan chamber 16 from which it is discharged into the filter bag 28. During on-the-floor cleaning operation, the handle 22 is oscillated through its normal operating range and also moves the converter closing member 75 therewith, however, the member 75 moves within the area defined by the arcuate wall 69 whereby the latter prevents the member 75 from obstructing the flow of dirt-laden air to the fan chamber 16. The recessed portion 59 in the air passageway 13 is in the path of the dirt-laden air stream and enlarges the air passageway adjacent the fan eye 19 to direct the dirt into the fan chamber 16.

During on-the-floor cleaning the barrier 51 is in its closed position and the arcuate portion 57 is arranged adjacent the rear periphery of the fan eye 19 to prevent accumulation of dirt in the air passageway rearwardly of the fan eye 19. The converter closing member 75 during on-the-floor cleaning is disposed at an angle to the air passageway 13, as shown for example in Figure 1, and prevents inserting the converter 62 into register with the fan eye 19.

In order to alter the cleaner to dusting tool operation the handle 29 is moved to its storage position shown in Figure 2. Movement of the handle to this position places the converter closing member 75 longitudinally of the air passageway 13 and forwardly of the motor shaft 17 between the belt 21 and the fan eye 19. The converter 62 is then inserted between the guides 70—70 and the arcuate end wall 67 moves the barrier 51 about the pin 52 inwardly of the air passageway 13. Continued movement of the converter 62 75 inserted in said air passageway.

4

causes the slot 69 to receive the converter closing member 75, and the opening 68 in the converter wall 64 is placed in register with the fan eye 19. When the converter 62 is completely inserted the member 75 closes the slot 69 in the converter and cooperates with the arcuate end wall 67 and the outer side wall 65 to seal the nozzle mouth 30 from the fan eye 19, and confines the flow of air in the converter 62 to the fan eye 19. Suitable dusting tools can be connected by means of a hose to the circular end 63 of the converter for cleaning surfaces solely by suction. The converter 62 being inserted at the rear of and longitudinally of the air passageway 13 permits movement of the cleaner on its wheels 35 and 36 by exerting a force on the dusting tool hose. Movement of the handle 29 from its off-the-floor cleaning position shown in Figure 2 is prevented while the converter is inserted due to the converter closing member 75 being disposed in the converter slot 69.

While I have shown and described but a single modification of my invention, it is to be understood that this modification is to be taken as illustrative only and not in a limiting sense. I do not wish to be limited to the particular structures shown and described, but to include all equivalent variations thereof except as limited by the scope of the claims.

30 I claim:

1. In a suction cleaner, a body having a nozzle, suction creating means, an air passageway connecting said nozzle and suction-creating means, and a port for inserting a converter into said air passageway, a cleaner propelling handle mounted on said body for movement to different positions, a converter insertable through said port into said air passageway and shaped to partly close the latter to said nozzle, completing means in said air passageway connected with said handle for movement therewith and shaped for interfitting engagement with said converter to completely close said passageway to said nozzle when said handle is in one of its positions and confine air flow through said converter to said suction creating means.

2. The structure described in claim 1 and means formed in said air passageway to receive said completing means to prevent the latter from obstructing the path taken by the air stream in said air passageway when said handle is in another position.

3. In a suction cleaner, a body having a nozzle, suction creating means, an air passageway connecting said nozzle and suction-creating means, and a port for inserting a converter into said air passageway, a surface agitator movably mounted in said nozzle, drive means in said passageway for moving said agitator, a cleaner propelling handle mounted on said body for movement to different positions, a converter insertable through said port and having an opening to receive said drive means, completing means in said air passageway connected with said handle for movement therewith and shaped to close said converter opening about said drive means when said handle is in one of its positions and confine air flow through said converter to said suction creating means.

4. The structure described in claim 3 characterized in that engagement of said completing means with the wall defining said converter opening prevents movement of said handle from its said one position while said converter is inserted in said air passageway.

5. In a suction cleaner, a body having a nozzle, suction creating means, an air passageway connecting said nozzle and suction-creating means, and a port for inserting a converter into said air passageway, a cleaner propelling handle mounted on said body for movement to different positions, a converter insertable through said port into said air passageway and shaped to partly close the latter to said nozzle, completing means in said air passageway connected with 10 said handle for movement therewith and shaped for interfitting engagement with said converter to completely close said passageway to said nozzle when said handle is in one of its positions and confine air flow through said converter to said 15

suction creating means, said interfitting engagement of said converter and completing means arranged at such an angle with respect to each other as to prevent movement of said handle from its said one position.
